UNITED STATES PATENT OFFICE.

JOHN T. REESE, OF SHIPMAN, VIRGINIA.

CHURN.

1,142,459.

Specification of Letters Patent.

Patented June 8, 1915.

Application filed July 27, 1914. Serial No. 853,513.

To all whom it may concern:

Be it known that I, JOHN T. REESE, a citizen of the United States, residing at Shipman, in the county of Nelson and State of Virginia, have invented certain new and useful Improvements in Churns; and I do hereby declare the following to be a full, clear, and exact description of the invention, such as will enable others skilled in the art to which it appertains to make and use the same.

This invention comprehends certain new and useful improvements in churns and has for its primary object to provide a new and improved form of churn which will be of extremely simple construction and operation as well as highly efficient in use.

Another object of the invention is to provide a churn in which will be included improved form of shaft and sleeve with a dasher of simple construction mounted thereon and improved means for supporting and operating the shaft and sleeve.

The invention has for another object to provide a device of this character in which the shaft and sleeve will be slidably engaged in the gear wheels mounted on the cover of the churn frame in the supporting casting carried by said cover or top of the churn frame, said gears being adapted to be rotated in reverse directions to revolve the shaft and sleeve with the dasher carried thereby in reverse directions.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is an elevation of the complete device, with the churn body in section, Fig. 2 is a longitudinal section through the operating mechanism of the churn, Fig. 3 is an enlarged elevation of the lower portion of the churn shaft and sleeve with the dashers mounted thereon, Fig. 4 is a detail sectional view on the plane of line 4—4 of Fig. 1, looking in the direction indicated by the arrow, and Fig. 5 is a detail sectional view on the plane of line 5—5 of Fig. 1, looking in the direction indicated by the arrow,

and Fig. 6 is a fragmentary detail view partly in section.

Referring in detail to the drawings by numerals, 1 designates a churn body provided with a cover 2 of conventional form and provided with a central opening 3 for the shaft and sleeve which will be later fully described. The churn body 1 rests upon a suitable base 4 from which upwardly directed standards 5 extend and are braced at their lower portions by the angular brace rods 6 connected therewith and with the base 4. A suitable circular top frame member is mounted upon the upper ends of the flanges 5 and provided with a seat 8 formed by cutting away a portion of the material around the inner upper edge of said top frame member 7 to receive the opposite ends of the cross bar 9 which is secured against movement by the members 10 which are pivotally connected to the cross bar 9 by staples 11 or other suitable securing members and has the tongues 12 formed at their free ends for engagement in staples 13 or 80 the like projecting from the outer face of the top frame member 7. It will be understood that the tongues 12 may be formed by making inwardly directed slots in one longitudinal edge of the latch members 10.

Secured upon the upper face of the cross bar is the casting 14, the base 15 of which rests upon the cross bar 9, while the upper end 16 of said casting is spaced from the base thereof by the upstanding vertical members 17 of the casting, through which is rotatably mounted the operating shaft 18 having a handle 19 formed upon its outer end, while the beveled gear 20 is mounted upon the inner end of said shaft and secured 90 in position by set screws 21 or the like carried by the rearwardly directed flange 22 of said beveled gear 20. The beveled gear 20 is engaged with the upper beveled gear 23 and also the lower beveled gear 24, as will 100 be readily understood by referring to the drawings.

The upper beveled gear 23 is mounted upon the dasher shaft 25 and has an annular flange 26 which is rotatably mounted in the 105 free forwardly extremity of the upper end 16 of the casting 14 and prevented moving longitudinally therein by means of the set screw 27 which is threaded in the outer extremity of the end 16 and has its inner end 110 engaged in the annular groove 28 in said flange 26, thereby securely retaining the

flange 26 and beveled gear 23 against vertical movement, allowing the same to freely rotate with the shaft 25, previously mentioned, to which the beveled gear 23 is securely fastened by the set screw 29, threaded in the flange 26 and adapted for engagement with the shaft 25.

The shaft 25 as well as the sleeve 30 formed upon the same is held against downward movement by means of the collar 31 mounted upon the upper end of said shaft 25 and bearing upon the upper face of the iron 16, said collar 31 being secured to the dasher shaft 25 by the set screws 32, which 15 will be readily understood by referring to the drawings.

The sleeve 30 has its upper end terminating a short distance below the upper beveled gear 23, while its lower end terminates a 20 spaced distance above the lower end of the shaft 25, said sleeve 30 being adapted to be rotated upon the shaft 25 by means of the beveled gear 24, previously mentioned which is engaged upon said sleeve 30 and locked for 25 rotation therewith by the longitudinal ribs 33 formed on the outer face of the sleeve 30 and slidably engaged in a longitudinal groove 34 formed in the central bore of the lower beveled gear 24 and the depending 30 flange 35 of said gear 24. It will be understood that the depending flange 35 of the lower beveled gear 24 depends through registering openings 36 in the base 15 of the casting 14 and in the transverse bar 9 and 35 is prevented from moving upwardly by a collar 37 positioned upon its lower end and secured in position by a set screw 38 or the like.

It will be readily seen that as the upper 40 and lower gears 23 and 24 are both rotated by the beveled gear 20, said gears 23 and 24 will be rotated in reverse directions, thereby causing reverse rotation of the shaft 25 and sleeve 30.

45 It will also cause a reverse rotation of the lower and upper dasher blades 39 and 40 caused by the shaft 25 and sleeve 30 respectively at the lower ends thereof. The dasher blades 39 are positioned at right angles and 50 secured to the block 41 threaded upon the lower extremity of the shaft 25, as clearly shown in Figs. 3 and 4, four blades 39 being employed. It will be apparent, however, that the blades may be positioned at different 55 angles and any number of blades 39 may be employed, if desired, and each blade is preferably provided with at least one opening 42 in its extended portion through which the contents of the churn may be 60 forced as the blades rotate to agitate said contents.

The dasher blades 40 are preferably positioned oppositely to the blades 39 and are secured to the sides of the sleeve 30 at the lower end thereof in any suitable manner, 65 as shown at 42, and I prefer to use the same number of blades 40 for the sleeve 30.

It will be apparent that the lower end of the sleeve 30 bears upon the upper face of the block 41 during operation of the device, 70 and it will be understood that the sleeve 30 as well as the shaft 25 may be readily removed by moving the same downwardly after loosening the set screw 32, of the collar 31. 75

When operation of the device has been continued, the latch members 10 may be readily disengaged from the staples 13 and the cross bar 9 with the casting 14 and all of the parts mounted therein raised until 80 the dasher blades 39 and 40 are removed from the churn body 1, it being understood that the shaft 25 and sleeve 30 pass through the central opening 3 of the churn cover 2, and said cover 2 will be raised by the dasher 85 blades 40.

While I have shown and described the preferred embodiment of my invention, it will be understood that minor changes in the details of construction, combination and arrangement of parts may be made without departing from the spirit and scope of the invention as claimed, or sacrificing any of the advantages thereof. 90

What is claimed is:—

A churn including a shaft, a squared block secured upon the lower extremity of said shaft, dasher blades secured to the sides of said squared block at right angles to one another and extended in corresponding directions with the inner vertical edge of each blade resting against the inner face of an adjacent blade, a sleeve rotatably mounted upon said shaft and adapted to rotate upon the upper end of said squared block, and 100 dasher blades on opposite sides of said sleeve adjacent the lower end thereof and extending at right angles to one another, the last mentioned blades being extended in opposite directions from the directions in 105 which the first mentioned blades are extended, the inner vertical edge of each of the second mentioned blades being engaged against the inner face of one of the adjacent second mentioned blades and is secured to 110 the same. 115

In testimony whereof I affix my signature in presence of two witnesses.

JOHN T. REESE.
